CLAIM

The ornamental design for a marble baseball game board, as shown and described.

DESCRIPTION

FIG. 1 is a perspective view of a marble baseball game board showing my new design;

FIG. 2 is a top plan view of the marble baseball game board of FIG. 1;

FIG. 3 is a side elevational view of the marble baseball game board of FIG. 1;

FIG. 4 is a rear end view of the marble baseball game board of FIG. 2;

FIG. 5 is the opposite side of the marble baseball game board of FIG. 2; and

FIG. 6 is the opposite front end of the marble baseball game board of FIG. 2.

The broken line showing of marbles is for illustrative purposes only.

FIG. 1.

FIG. 2.

FIG. 3.

FIG. 4.

FIG. 5.

FIG. 6.
